UNITED STATES PATENT OFFICE.

PARK BENJAMIN, OF NEW YORK, N. Y.

TELEPHONE-CASE.

SPECIFICATION forming part of Letters Patent No. 293,136, dated February 5, 1884.

Application filed October 29, 1883. (No model.)

To all whom it may concern:

Be it known that I, PARK BENJAMIN, of the city, county, and State of New York, have invented a new and useful Improvement in Cases 5 for Telephones, of which the following is a specification.

The invention consists in a telephone box or case constructed of glass or analogous vitreous material, and entirely inclosing the internal mechanism of the instrument. The said box or case is preferably made in two parts, one inclosing the electrodes, magnets, circuit-connections, or other internal mechanism of the instrument, the other constituting 15 the cover and containing the mouth-piece and mouth-piece orifice.

In the accompanying drawings is represented a form of telephone-transmitter to which I apply my invention by constructing the cover E 20 and the receptacle B, or either of them, of glass, in lieu of wood and iron or other material, respectively. This application exhibits one of the best means I now know for carrying the said invention into practical effect. 25 The particular telephone here shown, in its operative parts, is the invention of Daniel Drawbaugh, and to this extent is disclaimed by me. I am aware that an application for Letters Patent for the said telephone has been 30 filed by the said Drawbaugh, to which application I refer for all details of construction and operation.

Figure 1 of the drawings is a front view of a telephone-transmitter provided with my glass case, and having the cover and diaphragm 35 removed. Fig. 2 is a sectional view of said instrument on the line $x-x$ of Fig. 1. Fig. 3 is a transverse section on the line $y-y$ of Fig. 1.

Similar letters of reference indicate like 40 parts.

A is the base or back board of the instrument.

B is the main portion of the inclosing-case, which I construct of glass. I form this part 45 in the form shown, preferably in a glass-press or analogous molding-machine, by the aid of suitable dies, in the manner well known in the manufacture of pressed glassware. I am thus enabled to produce in the object while in 50 the press the necessary recesses, indentations, or holes. Such holes as cannot thus be made

may afterward be drilled; but it will be better so to design this part of the case that it may be formed at once in proper shape in the press. The form may, however, be varied, so 55 as to be produced by blowing or other means.

The recesses, indentations, &c., above referred to are respectively shown in the drawings as containing the rubber pads C, the induction-coil Q, the electrodes I J, the rod K, 60 and the ring or gasket F. The cover E, I also preferably form of glass or other vitreous material. It is provided with a mouth-piece orifice, G, and may have a flanged edge, as shown, to overlap the part B. It is detachably secured to the part B by bolts and nuts Y, or by any other convenient means.

The construction and operation of the telephone here shown as embodying my invention are as follows:

G' is the diaphragm, which may be of metal, or of glass or mica. It is secured between the cover E and part B of the case.

H is a bracket, of metal, fastened on the rear side of said diaphragm, and supporting an annular cup-shaped carbon electrode, I, in which rests a bell-shaped carbon electrode, J. A rod, K, extends down through an aperture in the part B and terminates in a metal knob, M.

N is another metal knob secured to a spring- 80 arm, O, which is attached by a screw, P, to the case B.

Q is the induction-coil.

D is a screw securing the rubber block C, there being three of such blocks entering sockets in the case B.

W is a hook to receive the ring of a receiving-instrument, which ring elevates the arm O, and so moves the carbons I and J out of contact.

The circuits in the instrument proceed as follows: From the battery to binding-post 1, by wire a to primary of induction-coil Q, by wire b to contact-piece T, to the diaphragm, to the bracket H, electrodes I and J, to rod 95 K, arm O, wire d , binding-post 2, and battery. Secondary wires e e' proceed from the induction-coil Q to the line binding-posts 3 4, from which posts branch wires f f' proceed to the posts 5 and 6, to which a receiving-instrument may be attached.

A telephone-case made of glass or analogous

vitreous material, as described, combines a large number of useful results, and by reason of such combination, as well as by reason of certain general properties of the material, differs essentially from a telephone-case constructed of any other substance. These results include: First, the case is itself an electrical insulator and insulates whatever is inclosed in it; second, the case is non-inflammable and projects adjacent inflammable material from danger of fire due to communication with an overheated telephone induction-coil or circuit-wire; such as might and often does occur when an electric-light wire becomes crossed with a telephone-wire and the powerful current on the former finds its way into the instrument; third, the case may be transparent, allowing easy inspection of all internal mechanism without taking the instrument apart; fourth, the case is of a material sufficiently heavy to oppose by its inertia, when suitably supported, as in the instrument shown in the drawings, jars or shocks communicated to the partition whereon the telephone may be secured; fifth, the case is formed of a material cheaper than metal or fine woods, which may be molded or pressed into shape as easily as the former; sixth, the case may be ornamented by coloring introduced into the body of the material; seventh, all parts of the case, including the cover, being made of glass, the instrument is substantially wholly inclosed in an insulated non-inflammable envelope; eighth, the instrument may be placed in a position exposed to the weather without injury, the only care required being to hermetically seal the joints by suitable cement or otherwise; ninth, the glass case protects the working parts of the instrument from the effects of moisture, and is not liable to contract or expand through differences in temperature; tenth, the glass may be treated by any well-known toughening process, so as to render it exceedingly strong, and not liable to rupture from shocks or otherwise.

45 I claim as my invention—

1. A telephone-case formed of glass or similar vitreous material, provided with suitable recesses, indentations, or apertures for the reception of the working parts of the instrument, substantially as described. 50
2. A telephone-case formed of glass or similar vitreous material, pressed or molded into substantially a block, which block is provided with suitable recesses, indentations, or apertures for the reception of the working parts of the instruments, substantially as described. 55
3. A telephone box or case having a detachable cover containing a mouth-piece and mouth-piece orifice, and a receptacle containing suitable recesses, apertures, or indentations for the reception of the working parts of the instrument, and a means of connecting said cover and receptacle, said receptacle and cover being formed of glass or similar vitreous material, substantially as described. 60
4. In a telephone, the receptacle B, provided with recesses, indentations, or apertures for the reception of the working parts of the instrument, substantially as described, and made of pressed or molded glass or similar vitreous material. 65
5. In a telephone, the cover E, having a mouth-piece and a mouth-piece opening, substantially as set forth, and made of pressed or molded glass. 75
6. In a telephone, a glass mouth-piece, substantially as described. 75
7. A telephone box or case constructed of transparent material, substantially as described. 80
8. A telephone box or case constructed of transparent non-inflammable material, substantially as described. 85
9. A telephone box or case constructed of transparent non-inflammable insulating material, substantially as described. 85

PARK BENJAMIN.
